UNITED STATES PATENT OFFICE.

PHILIP MUELLER AND ANTON C. SCHUERMANN, OF DECATUR, ILLINOIS, ASSIGNORS
TO ADOLPH MUELLER, TRUSTEE, OF DECATUR, ILLINOIS.

INTEGRAL STOP.

Application filed November 4, 1919. Serial No. 335,683.

To all whom it may concern:

Be it known that we, PHILIP MUELLER and ANTON C. SCHUERMANN, citizens of the United States, residing at Decatur, in the county of Macon and State of Illinois, have invented new and useful Improvements in Integral Stops, of which the following is a specification.

This invention relates to stops for basin and other fittings, and has as its main object to provide a fitting, which may be, as here shown, the inlet or supply pipe leading to a cock or faucet, with an integral stop for cutting off or regulating the flow of water. Our integral stop is designed to take the place of the handle cocks now generally used, and which are objectionable in that they mar the appearance of the fitting, or are located in some inaccessible place. Our improved stop may be placed in a fitting which connects the cock or faucet with the service pipe, so that access may be readily had thereto, and the appearance of the fitting is in no way mitigated against.

The construction of stop herein described is such that the removable parts of the stop may, for purposes of renewal or repair, be easily withdrawn from the basin fitting without disassembling the several parts. The stop is very simple in construction, comprises a relatively small number of parts, and may be manufactured at a relatively low cost, the construction being such that the supply pipe together with the integral stop applied thereto may be sold as a single article of manufacture when so desired.

The above and other objects of our invention are obtained by the structure described in the following specification and illustrated in the accompanying drawings, and wherein—

Figure 1 is an elevational view of a basin cock and fitting, the latter being provided with our improved integral stop.

Figure 2 is a longitudinal sectional view through the fitting and stop shown in Figure 1.

Figure 3 is a perspective view of the several parts of which our improved stop is composed, these parts being shown disassembled.

Figure 4 is a partial view of the fitting showing another form of integral stop applied thereto.

Figure 5 is a longitudinal sectional view

through a fitting having a regulating device and integral stop.

Figure 6 is a longitudinal section through an angle coupling showing our improved stop applied thereto.

Figure 7 is a view, similar to Figure 2, showing a slightly different embodiment of our invention.

Figure 8 is a sectional view showing our improved stop applied to a globe valve.

Referring to the drawings by numerals, and particularly to Figures 1, 2 and 3, like characters representing similar parts in the several views, 10 designates a fitting having connected to the outer end thereof by means of a coupling nut 11 a cock or faucet 12 which may be of any suitable or well-known construction. Within the fitting 10, as will be seen from Figure 2, is an integral web or diaphragm 13, a portion of which extends longitudinally of the pipe, which portion is provided with a central circular opening having one edge suitably beveled to form a valve seat 14 through which water is adapted to pass to the cock.

The wall of the fitting adjacent the seat is preferably flattened on its outer surface to form a level surface and preferably, as here shown, thickened inwardly to give a substantial valve mounting, such as will sustain the valve parts, and such thickened section has an orifice 15 therethrough, the axial or longitudinal center of said orifice being in alignment with the center of said seat 14.

16 designates a plug which, in the present embodiment, is substantially of the same external diameter throughout its length and the plug has an external thread complementary to the internal threads of the orifice 15, so that the plug may be screwed into place in said orifice. To permit turning of the spanner plug 16, it is provided at its outer end with a plurality of radial notches 17 forming suitable wrench holds for a spanner wrench or the like. The spanner plug 16 has a central longitudinal opening therethrough suitably threaded to receive complementary screw-threads 18 upon the intermediate portion of a valve stem 19 carrying at its inner end a valve head 20 which may be of any suitable construction.

The outer end of the spanner plug 16, as will be seen from Figure 2, has an enlarged bore 21 internally screw-threaded and receiving a washer or packing ring 110

22 which surrounds the unthreaded portion of the stem 19, the washer being forced tightly into place against the shoulder at the inner end of the bore 21 to provide a 5 fluid-tight joint between the stem and the plug by means of a packing nut 23 adapted to be screwed into said enlarged bore. The upper end of the stem 19 is polygonal or squared in shape for the reception of a suitable wrench or other tool for turning the 10 stem to move the valve-head 20 to and from its seat as desired. 24 designates a closure cap preferably of the same material and having the same finish as the fitting to which 15 it is applied, and this cap is internally threaded so that it may be screwed over the outer end of the spanner plug 16 to cover the stem and plug and give to the pipe a neat and pleasing appearance, and to prevent 20 tampering with the stop valve. About the orifice 15 in the fitting 10 is an annular groove adapted to receive a packing-ring or washer 25 against which the lower edge of the closure cap is adapted to be forced to 25 form a fluid-tight joint between the plug and the fitting.

It is, of course, obvious that our invention 30 may be applied to various forms of basin fittings and that the specific structure of the stop may be more or less varied to suit 35 the conditions under which it is to operate, and for purposes of illustration, we have shown in the accompanying drawings, several embodiments of our invention which involve substantially the same principles of 40 construction as the internal stop shown in Figures 1 to 3.

In Figure 4, the construction of integral 45 stop is very similar to that disclosed in Figure 2, except that the central opening through the spanner plug is of the same diameter throughout its length, no packing gland being provided between the stem and the plug, and the plug has, intermediate its 50 ends, an external circumferential flange 26 which is adapted to engage in the bottom of the annular groove in the fitting about the orifice 15 to limit the inward movement of the spanner plug. This construction may be used where a very simple plug is desired.

In Figure 5, we have shown a fitting provided with an integral stop and a regulating device for cutting off and controlling the flow of water through the pipe, the regulating device and stop being, in the present instance, very similar in construction except for the valve members carried on the inner ends of the stems of the respective devices. The integral stop portion (shown on 55 the left-side of the pipe in this figure) is very similar to the integral stops shown in Figures 2 and 4, differing only in proportion of the parts and in that the valve-head 27 is provided with a hole or passage 60 65 28 extending from the periphery to the

center of the valve-head and terminating in an outwardly flaring recess in the outer face of the valve-head, the walls of the recess forming a valve seat 29. The integral regulating device is located in 70 diametrical alignment with the stop and is very similar to the construction of integral stop shown in this figure. The stem 30 of the regulating device is provided, however, with a needle valve 31 which is in alignment 75 with its seat 29 in the valve-head 27 with which it can be brought into engagement by turning the valve stem 30 in the proper direction. It will be seen that when a full or unrestricted flow of water is desired 80 through the fitting, the stems 19 and 30 of the stop and regulating devices are rotated in a direction to withdraw the valve head 27 and the needle valve 31 from each other, and so permit water to flow freely over the 85 valve-seat 14. When it is desired to restrict the flow of water, the stem 19 of the integral stop is rotated, causing the valve-head 27 due to the threaded engagement 90 between the stem and the plug 16, to move rectilinearly and into engagement with the seat 14 and the control of water is then regulated by advancing or withdrawing the needle valve 31 relative to the opening or seat 29. To shut off the flow of water 95 completely through the pipe, the head 27 of the integral stop is brought to its seat 14 and the needle valve 31 is brought to its seat 29 in the head 27.

Referring to Figure 6, we have disclosed 100 our improved stop applied to an angle coupling, the latter having a diaphragm 32 extending transversely across one of the branches of the through opening 32'. At the elbow of the coupling, and in alignment 105 with the inlet opening of the coupling is located the orifice 15 which receives the plug 16 together with the valve 20.

In Figure 7, the construction of integral 110 stop is very similar to that shown in the preceding views. It will be noted that in this figure, the inner end of the packing nut 23, that is the end which engages against the washer or packing 22, is somewhat conical in shape, so that the packing 22 is forced 115 closely about the stem 19.

Figure 8 is a view quite similar to that shown in Figure 6, but illustrates our improved stop as applied to a globe valve.

It will be seen that in each of the embodiments of our invention herein disclosed, our invention consists generally in providing a valve seat in the basin fitting, a spanner plug screwed into an orifice in the side of the fitting, and a stem rotatably mounted in the plug, the stem being connected to a suitable valve head which upon turning movement of the stem is adapted to be brought into engagement with its seat. A closure top is threaded over the 120 125 130

- upper end of the spanner plug to protect the plug and stem, prevent lodgment of dirt, and to give a proper sanitary finish to the fitting, and preferably the spanner plug is provided with a gland or stuffing box to give a watertight joint between the valve stem and the plug. The appearance and symmetry of the fitting is in no way marred, there being no unsightly protrusions, or extensions, and the valve stem may be quickly and readily turned to shut off or regulate the flow of water, it being merely necessary to remove the closure cap and apply a wrench to the upper end of the valve stem. The plug and valve stem, in the preferred form of our embodiment, together with the packing, may be removed from the orifice in their assembled condition.
- 20 While we have shown a particular construction, it will be understood that variations in mechanical details may be made without departing from the spirit of our invention, and we do not, therefore, limit ourselves to the exact details shown and described, except in so far as we are limited by the terms of the appended claims.
- What is claimed is:—
1. A fitting of the class described having a section of its wall thickened inwardly to give a substantial plug seat and having an orifice through said thickened section, a valve seat below said thickened section, a plug seated in the orifice in said thickened section and having an opening therethrough, a valve stem mounted in said plug, and a valve on said stem adapted to engage said valve seat.
  2. A fitting of the class described having a section of its wall countersunk and thickened to give a substantial plug seat and having an orifice through said thickened section, a valve seat below said thickened section, a plug seated in the orifice in said thickened section and having an opening therethrough, a valve stem mounted in said plug, a valve on said stem adapted to engage said valve seat, and a closure cap secured to the outer end of said plug.
  3. A fitting of the class described having a section of its wall countersunk and thickened inwardly to give a substantial plug seat and having an orifice through said thickened section, a valve seat below said thickened section, a plug threaded at its lower end in the orifice in said thickened section and having an opening therethrough, a valve stem mounted in said plug, a valve on said stem adapted to engage said valve seat, and a closure cap threaded to the outer end of said plug.
  4. A fitting of the class described having a section of its wall thickened inwardly into the bore of the fitting to give a substantial plug seat and having an orifice through said
  - 5 thickened section, a valve seat below said thickened section, an exteriorly threaded plug seated at its lower end in the orifice in said thickened section and having an opening therethrough, a valve stem mounted in said plug, a valve on said stem adapted to engage said valve seat, packing surrounding the said plug exteriorly of the fitting, and a closure cap secured to the outer end of said plug and seated against said packing.
  6. A fitting of the class described having a section of its wall thickened to give a substantial plug seat and having an orifice through said thickened section, a valve seat below said thickened section, a threaded plug seat in the orifice in said thickened section and having an opening therethrough, a valve stem mounted in said plug for reciprocation, a valve on said stem adapted to engage said valve seat, a packing in said plug about said valve stem, a packing surrounding said plug and seated on the outer wall of said fitting, and a closure cap secured to the outer end of said plug and engaging said exterior plug packing.
  7. A fitting of the class described having an integral thickened section projecting inwardly into the bore of said fitting and provided with an orifice, an integral diaphragm in the bore of said fitting in alignment with said thickened section and having a valve seat formed therein, an exteriorly and interiorly threaded plug having its lower end engaged with the orifice in said thickened section, a valve stem in threaded engagement with the opening through said plug, a valve on said valve stem adapted to engage the seat in said diaphragm, and a closure cap threaded to the upper end of said plug and seated against the outer wall of said fitting.
  8. As a new article of manufacture, a pipe section having an integral wall portion projecting inwardly into the bore of the pipe, and having an orifice therethrough to form a valve mounting, and an integral diaphragm formed in the bore of the pipe and having a valve seat in line with the orifice in said thickened portion.

9. As a new article of manufacture, a pipe section having a portion of the outer surface of its wall flattened, and an integral thickened section projecting inwardly into
5 the bore of the pipe from said flattened area, said thickened section having an orifice therethrough to form a valve mounting, and an integral diaphragm formed in the bore of the pipe and having a valve seat in line with the orifice in said thickened portion. 10
In testimony whereof we have hereunto set our hands.

PHILIP MUELLER.

ANTON C. SCHUERMANN.
